FASTENER STRINGER AND METHOD OF
PRODUCING THE SAMELouis H. Morin, Bronx, N. Y., assignor of one-half
to Davis Marinsky, Bronx, N. Y.

Application June 15, 1945, Serial No. 599,684

18 Claims. (Cl. 154—91)

1

This invention relates to separable fastener stringers. More particularly, the invention deals with a novel end construction for the tapes of the stringers and the method of producing the same to provide a simple, strong, as well as neatly finished end on the stringer tapes and a method which will materially simplify the production of fastener tapes having the separator ends thereon in producing what is generally referred to as detachable fasteners where the two stringers are completely separated from each other as in jacket and similar installations of fasteners of this kind.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side view of one end portion of a fastener showing the box part of a separator thereon.

Fig. 2 is a section on the line 2—2 of Fig. 1.

Fig. 3 is a section on the line 3—3 of Fig. 1.

Fig. 4 is a diagrammatic view illustrating the method of attaching industrial tape to stringer ends and in severing the tape to form the reinforced tape mountings on said stringer ends; and

Fig. 5 is a view similar to Fig. 4 showing only a part of the construction and illustrating a different arrangement of stringers in the attachment of industrial tape to the ends thereof.

In fasteners of the type and kind under consideration and, particularly, where what are known as separators are mounted on the stringer ends, such as pin and box parts employed to couple the stringer ends, difficulty has been experienced in forming a finished end on the stringer tape. One method of procedure has consisted of folding the tape end backwardly upon itself and then attaching the pin and box parts to the folded tape at the beaded edge.

To simplify this procedure, I employ a simple method of securing what is commonly referred to as industrial tape, one type of which is generally known as "Texcel," to a short-cut end of a stringer prior to the attachment of pin and box parts of a separator or any other end stop construction or coupling to the stringer. The industrial or finishing tape is preferably folded over the outer end of the stringer tape to form a neat and finished end on the stringer tape, as well as to seal the cut end against unravelling.

2

Industrial tapes of the type and kind under consideration can be made in colors similar to or in harmony with the colors employed on the stringer tape, so that the characteristics of the industrial tape become substantially invisible aside from the difference in texture which may prevail in this tape as compared with the stringer tape.

In Fig. 1 of the drawing, I have shown at 10 the tape of one stringer of a pair of fastener stringers, on the beaded edge 11 of which are attached scoops 12, as in other devices of this kind. The scoops 12 terminate short of the tape ends as clearly seen in Fig. 1 for attachment of the tapes to garments to provide the mounting of end stops thereon or for attachment of the parts of what are known as separators, for example, the box part 13 of a separator, which is shown attached to the beaded edge 11 beyond the scoops 12. Box and pin couplings are well known in the art and, for this reason, only one stringer is shown, namely the stringer to which the box part 13 is attached. It will be understood, however, that the companion stringer, to which the pin part is attached, will be constructed in the same manner, as more clearly hereinafter described.

Prior to attachment of the box part 13 to the stringer tape 10 or the beaded edge 11 thereof, 30 the protruding end portion 14 of the tape has a reinforcing and finishing strip or tape 15 attached thereto. The strip 15 is in the form of a wide band folded centrally, as seen at 16, note Fig. 3, over the outer end of the tape 10 or the end portion 14 thereof and then extending onto and secured to opposite sides of the tape 10 in forming side portions 17 and 18, as clearly shown in Fig. 3 of the drawing. The reinforcing strip sides 17 and 18 extend over the bead 35 11 and around the outer surfaces of the bead, as seen at 19 and 20. Furthermore, the strip sides 17 and 18 also extend slightly over the other edge 21, as indicated at 22 and 23 in Fig. 2 of the drawing.

40 The reinforcing and finishing strip 15 is generally known as industrial tape, one brand of which being identified as "Texcel." However, any type and kind of tape of this kind can be used so long as it has properties to establish an adhesion to the stringer tape, at least sufficiently to maintain the assemblage and attachment to a support or until end stops or couplings, such as the coupling 13, has been attached thereto.

45 It is preferred that the type of adhesive em-

ployed be one which will maintain a more or less permanent adhesion with the stringer tape and one which will satisfy the uses to which the fastener may be subjected. Different types and kinds of end stops of couplings are employed on fasteners and these are either pinched on or cast directly upon the beaded edge portion 11 of the tape. In the present construction, it will also envelope the reinforcing tape which is disposed on the beaded edge 11. In Figs. 1 and 2, the box part 13 is in the form of a die casting which can be formed directly upon the beaded edge in the manner clearly illustrated in section in Fig. 2.

In producing stringers of the type and kind under consideration, I can follow one of two different procedures with respect to arrangement of stringers in attachment of the reinforcing strip or tape 15 thereto, i. e., with the stringer tapes arranged edge to edge with the scoops extending in common directions from adjacent tapes, as shown in Fig. 4, or with pairs of stringer tapes coupled together and outer edges of the tapes of adjacent pairs in abutting relation to each other, as illustrated in Fig. 5.

The method of procedure in attachment of the strip 15 will be the same in Figs. 4 and 5. However, this method is diagrammatically illustrated in Fig. 4. It comprises folding a relatively wide strip 15' from a roll 24 of industrial tape, as indicated at 25, to extend over opposed side surfaces of a plurality of stringer tapes which, for illustrative purposes, are shown at 10a, 10b, 10c and 10d, one tape 10e being shown prior to insertion between the folds 25 of the strip 15'.

The scoops of the stringer tapes 10a—10e are all arranged at the right side of the tapes in bringing said tapes into close proximity to each other with the edges 21 spaced slightly from the beads 11 of adjacent tapes. The assemblages, as shown, are then passed between an opposed pair of rollers, one roller of the pair being shown at 26 in Fig. 4 of the drawing and these rollers firmly press the strip 15', or the side portions thereof, upon opposed sides of the stringer tapes and around the beads 11, producing on the resulting fastener the sides 17 and 18. A large number of stringers may be united with the folded strip 15' and then, at a predetermined point or station spaced with respect to the rollers 26, the strip 15' is cut by a suitable cutter 27 at the sections 28 between the edges 21 and the beads 11 and preferably centrally of these sections so as to leave the protruding ends, which result in extension of the tape sides 17 and 18 around the bead, as seen at 19 and 20, and over the edge 21, as seen at 22 or 23.

In the pressing operation, through the medium of the rollers 26 or immediately thereafter, heat may be applied particularly with some types and kinds of tapes. However, with other tapes, the need of heat is not essential. It will also be apparent that, in the assemblage of the stringer tapes, as shown in Fig. 4, the tape edges 21 will be disposed at one side of the scoops 12. However, beyond the end scoops, the ends 14 will be substantially in alinement with each other.

In Fig. 5 of the drawing, the method as disclosed in Fig. 4, is followed in substantially the same manner with the exception that pairs of stringers, such for example, as the pair 10f, 10g and the pairs 10h and 10i are joined together by coupling of the scoops, prior to attachment of the strip 15'' thereto. This construction provides wider sections 28' between the stringers of each pair which necessitates two cuttings of the strip

15'' on the lines 29 and 30 and also necessitates a single cut 31 between outer edge portions 21' of adjacent pairs of stringers. The result, however, will produce finishing tapes 15, similar to those illustrated in Figs. 1-3 inclusive.

It will be understood that, in carrying out the method, the stringer tape ends are cut to a predetermined length beyond the end scoops and these cut ends are arranged in alinement in the application of the finishing and reinforcing tape thereto. In referring to industrial tapes as illustrating one type and kind of tape that can be used, other tapes more commonly referred to as heat sealing tapes can be used and one of these tapes is identified as "Bondex." Still further, what is known as pressure sealing tapes can also be used.

In connection with the method shown in Fig. 5, it will be apparent that, in some instances, and with some types and kinds of stringers, the severing of the strip or tape 15'' between the tapes of each pair, as at 29 and 30, need not be performed, particularly when it is practical to use the finishing strip as a joining strip for the tape ends as and when it would be practical to do this in making installations of the fasteners in predetermined uses. In this connection, it will be apparent that other means, in addition to the strip 15', may be employed, for example such as an end stop construction or reinforcement die cast or otherwise applied to the beaded edge portions or to the tape ends themselves.

Having fully described my invention, what I claim as new and desire to secure by Letters Patent is:

1. The method of forming and finishing tape ends of separable fastener stringers which comprises cutting tape ends to form extensions of predetermined length beyond end scoops of the stringers, arranging stringer tapes in edge to edge relationship with said ends in common alinement, then folding an elongated strip over said tape ends to dispose side portions of the strip upon opposed sides of the tape ends, securing the strip to said tape ends by applied pressure, and then severing said strip intermediate adjacent tape ends in producing on the tape ends reinforcing and finishing strips, the folds of which are disposed at outer edges of said tape ends.

2. The method of forming and finishing tape ends of separable fastener stringers which comprises cutting tape ends to form extensions of predetermined length beyond end scoops of the stringers, arranging stringer tapes in edge to edge relationship with said ends in common alinement, then folding an elongated strip over said tape ends to dispose side portions of the strip upon opposed sides of the tape ends, securing the strip to said tape ends by applied pressure, then severing said strip intermediate adjacent tape ends in producing on the tape ends reinforcing and finishing strips, the folds of which are disposed at outer edges of said tape ends, and extending cut edges of the strip around side edge portions of the stringer tape.

3. The method of forming and finishing tape ends of separable fastener stringers which comprises cutting tape ends to form extensions of predetermined length beyond end scoops of the stringers, arranging stringer tapes in edge to edge relationship with said ends in common alinement, then folding an elongated strip over said tape ends to dispose side portions of the strip upon

opposed sides of the tape ends, securing the strip to said tape ends by applied pressure, then severing said strip intermediate adjacent tape ends in producing on the tape ends reinforcing and finishing strips, the folds of which are disposed at outer edges of said tape ends, extending cut edges of the strip around side edge portions of the stringer tape, and then applying a body portion to the scoop edge portion of each stringer beyond an end scoop and upon the finishing strip at said edge portion.

4. The method of forming and finishing tape ends of separable fastener stringers which comprises cutting tape ends to form extensions of predetermined length beyond end scoops of the stringers, arranging stringer tapes in edge to edge relationship with said ends in common alinement, then folding an elongated strip over said tape ends to dispose side portions of the strip upon opposed sides of the tape ends, securing the strip to said tape ends by applied pressure, spacing adjacent stringer tapes one from the other in attaching the strip thereto to form stringer joining sections, then severing the strip at said sections, and then applying an end stop body to the stringer end and said strip beyond an end scoop of the stringer.

5. The method of forming and finishing tape ends of separable fastener stringers which comprises cutting tape ends to form extensions of predetermined length beyond end scoops of the stringers, arranging stringer tapes in edge to edge relationship with said ends in common alinement, then folding an elongated strip over said tape ends to dispose side portions of the strip upon opposed sides of the tape ends, securing the strip to said tape ends by applied pressure, spacing adjacent stringer tapes one from the other in attaching the strip thereto to form stringer joining sections, then severing the strip at said sections, and then die casting a coupling member on said stringer end and strip beyond an end scoop of the stringer.

6. The method of forming and finishing the ends of separable fastener stringers, which comprises forming the tapes of the stringers with predetermined ends extending beyond end scoops disposed on the beaded edge of the stringer tapes, then arranging stringer tapes successively in edge to edge relationship with said ends in common alinement and spaced apart, then folding and pressing a gummed finishing strip upon said ends with the fold of the strip arranged at outer alined edges of said tape ends, said finishing strip forming between the spaced edges of the tape ends joining sections, and then severing the strip at each adjoining section to form independent stringers with said finishing strip disposed on said ends thereof.

7. The method of forming and finishing the ends of separable fastener stringers, which comprises forming the tapes of the stringers with predetermined ends extending beyond end scoops disposed on the beaded edge of the stringer tapes, then arranging stringer tapes successively in edge to edge relationship with said ends in common alinement and spaced apart, then folding and pressing a gummed finishing strip upon said ends with the fold of the strip arranged at outer alined edges of said tape ends, said finishing strip forming between the spaced edges of the tape ends joining sections, then severing the strip at each adjoining section to form independent stringers with said finishing strip disposed on said ends thereof, and then applying a die cast

body to the beaded edge of said ends and the strip disposed on said beaded edge.

8. The method of forming and finishing the ends of separable fastener stringers, which comprises forming the tapes of the stringers with predetermined ends extending beyond an end scoop disposed on the beaded edge of each stringer tape, then arranging stringer tapes successively in edge to edge relationship with said ends in common alinement and spaced apart, then folding a finishing strip centrally and longitudinally, arranging tape ends within the fold of said strip, then applying pressure and heat to opposed sides of the strip in securing the same to opposed side surfaces of said tape ends, forming of the strip between spaced edges of the stringer ends coupling sections temporarily uniting adjacent stringers, and then severing the strip at said sections to form independent stringers with the reinforcing and finishing strip thereon.

9. The method of forming and finishing the ends of separable fastener stringers, which comprises forming the tapes of the stringers with predetermined ends extending beyond an end scoop disposed on the beaded edge of each stringer tape, coupling the scoops to stringers to form pairs of stringers, arranging pairs of stringers in edge to edge relationship with said ends in common alinement, then folding a finishing strip over said ends of the stringers, applying pressure and heat to the folded strip and stringers in securely mounting the strip on said stringer ends, and then severing the strip intermediate pairs of the stringers.

10. The method of forming and finishing the ends of separable fastener stringers, which comprises forming the tapes of the stringers with predetermined ends extending beyond an end scoop disposed on the beaded edge of each stringer tape, coupling the scoops to stringers to form pairs of stringers, arranging pairs of stringers in edge to edge relationship with said ends in common alinement, then folding a finishing strip over said ends of the stringers, applying pressure and heat to the folded strip and stringers in securely mounting the strip on said stringer ends, then severing the strip intermediate pairs of the stringers, and intermediate the stringers in each pair.

11. The method of forming and finishing the ends of separable fastener stringers, which comprises forming the tapes of the stringers with predetermined ends extending beyond an end scoop disposed on the beaded edge of each stringer tape, coupling the scoops to stringers to form pairs of stringers, arranging pairs of stringers in edge to edge relationship with said ends in common alinement, then folding a finishing strip over said ends of the stringers, applying pressure and heat to the folded strip and stringers in securely mounting the strip on said stringer ends, then severing the strip intermediate pairs of the stringers, and then applying coupling members to the tape ends and the strip secured thereto.

12. The method of forming and finishing the ends of separable fastener stringers, which comprises forming the tapes of the stringers with predetermined ends extending beyond an end scoop disposed on the beaded edge of each stringer tape, coupling the scoops to stringers in edge to edge relationship with said ends in common alinement, then folding a finishing strip over said ends of the stringers, applying pressure and heat to the folded strip and stringers in securely mounting the strip on said stringer ends, then

severing the strip intermediate pairs of the stringers and intermediate the stringers in each pair, and then applying coupling members to the tape ends and the strip secured thereto.

13. The method of finishing and reinforcing the ends of the tapes of separable fastener stringers having pin and box coupling parts secured to the beaded edge of said tapes, which comprises forming the tapes of predetermined length beyond an end scoop of a stringer, folding a finishing strip over the outer edge of said tape end to dispose sides of the strip upon and securing the same to opposed surfaces of the major portion of said tape ends including said beaded edge, and then attaching a coupling part to the beaded edge of said end of the stringer tape.

14. A stringer for separable fasteners comprising a tape having a beaded edge with scoops spaced longitudinally of said edge and terminating short of one end of the tape to form a mounting end, a folded finishing and reinforcing strip arranged upon and secured to said mounting end of the stringer tape, the fold of said strip being disposed at the outer edge of said mounting end, side portions of the strip being disposed upon opposed surfaces of said tape and including the bead thereof, and a coupling body arranged upon the beaded edge portion of said tape end and the strip secured thereto.

15. A stringer for separable fasteners comprising a tape having a beaded edge with scoops spaced longitudinally of said edge and terminating short of one end of the tape to form a mounting end, a folded finishing and reinforcing strip arranged upon and secured to said mounting end of the stringer tape, the fold of said strip being disposed at the outer edge of said mounting end, side portions of the strip being disposed upon opposed surfaces of said tape end including the bead thereof, a coupling body arranged upon the beaded edge portion of said tape end and the strip secured thereto, and said strip having side edges extending over side edge portions of the tape.

16. An end construction for the tapes of separable fastener stringers employing scoops spaced longitudinally of a beaded edge of the stringer tape, the tape having an end disposed beyond an end scoop of the stringer, means reinforcing and

finishing said end of the tape, said means comprising a strip secured to opposed surfaces of said tape end including the bead thereof, the strip having a fold disposed at the outer edge of said tape end, the fold finishing said tape end, and side portions of the strip extending onto side edges of said tape end.

17. An end construction for the tapes of separable fastener stringers employing scoops spaced longitudinally of a beaded edge of the stringer tape, the tape having an end disposed beyond an end scoop of the stringer, means reinforcing and finishing said end of the tape, said means comprising a strip secured to opposed surfaces of said tape end including the bead thereof, the strip having a fold disposed at the outer edge of said tape end, the fold finishing said tape end, side portions of the strip extending onto side edges of said tape end, and a die cast member arranged upon said tape end and the strip disposed thereon.

18. An end construction for the tapes of separable fastener stringers employing scoops spaced longitudinally of a beaded edge of the stringer tape, the tape having an end disposed beyond an end scoop of the stringer, means reinforcing and finishing said end of the tape, said means comprising a strip secured to opposed surfaces of said tape end including the bead thereof, the strip having a fold disposed at the outer edge of said tape end, the fold finishing said tape end, side portions of the strip extending onto side edges of said tape end, a die cast member arranged upon said tape end and the strip disposed thereon, and said member extending along the bead of said tape end and including a part protruding beyond the edge of said bead.
